BOILER SECTION

Louis N. Hunter, Johnstown, Pa., assignor to The
National Radiator Company, a corporation of
Maryland

Application February 10, 1937, Serial No. 125,045

1 Claim. (Cl. 122—225)

This invention relates to boiler sections, and particularly to a boiler section provided with internal means for reducing the moisture content of the steam generated in the boiler section. The invention is primarily applicable to sectional boilers as distinguished from boilers of single or one-piece construction.

It is generally recognized that in the generation of steam in a boiler a certain amount of water in the form of small drops or particles is carried along with the steam. It is also generally recognized that the presence of such water particles or drops in the steam is not desirable. Steam which is relatively free from such suspended particles is frequently referred to as "dry steam," whereas steam which contains a considerable amount of such water is referred to as "moist" or "wet steam."

The plane of separation between the water space in a boiler and the steam space is quite generally termed the "water line" and is also known as the "steam releasing area" or "steam releasing surface." When steam leaves the water surface or the water line, it has a tendency to carry with it the small particles or droplets of water above referred to. One factor which determines the amount of water carried off is the rate of firing of the boiler. The higher the firing rate the greater the rate at which steam is generated and there is, therefore, a greater velocity of the steam leaving the surface of the water, tending to entrain a greater amount of water. Another factor which determines the amount of moisture in the steam is the relation of the steam releasing area in proportion to the capacity of the boiler. If the steam-releasing area of the boiler is relatively small as compared with the amount of steam being generated, the steam will leave the water line at a greater velocity because of its concentration over a small area and, therefore, entrain more water.

A third factor affecting the carrying off of small particles of water is the circulation of the water in the boiler below the water line. As the steam is generated, convective currents, of course, are set up in the water, resulting in the presence of upwardly moving currents of water and downwardly moving currents. The upwardly moving currents are the hotter ones and steam is released more rapidly over these areas of upwardly moving currents than at other points on the surface of the water. This results in the tendency for the steam generated at these points to carry a greater moisture content and this is aggravated by the currents of water itself. The heating en-

gineer should be qualified to determine the proper size of boiler so that it does not have to be fired at an excessive rate, and the boiler designer endeavors to provide an adequate steam-generating surface for the amount of steam required.

The third factor, however, i. e., the movement of the currents of water within the boiler itself, is inherent to the operation of the boiler and the elimination of wet steam from this source has heretofore presented a problem. This is particularly true in the case of sectional boilers used in heating plants where the requirements on the boiler fluctuate widely with variations in the outside temperature and where, for economical purposes, the boiler sections should be designed for use either in hot water, steam or vapor heating systems.

According to the present invention, it is proposed to provide baffles which are generally inclined with respect to the water line located across the areas of greatest upward movement of the water, i. e., the areas where steam is generated at the highest rate, so arranged that all of the steam generated in this area is deflected in a generally horizontal direction and then caused to reverse its flow at a sharp angle one or more times before reaching the steam take-off of the boiler. By deflecting the direction of flow of the steam sharply, the entrained particles of water having a greater mass, change their direction less readily and are, therefore, removed by this kinetic action from the steam. The baffles are so constructed that the steam cannot avoid the effect of them so long as a proper water line is maintained within the boiler. At the same time, their arrangement and disposition is such that if it is desired to use the boiler in a water heating system instead of a steam heating system, they offer no impediment to a proper circulation of water through the boiler, nor will they become loaded with solids precipitated from the water.

The invention may be readily understood by reference to the accompanying drawings which illustrate one typical form of section to which the present invention is applicable having my invention applied thereto.

In the drawings:

Figure 1 represents a vertical transverse section through a boiler section embodying my invention, the section being in a plane parallel with the two side faces of the section;

Figure 2 is a transverse section in the plane of line II—II of Figure 1, and

Figure 3 is a fragmentary sectional view simi-

lar to Figure 1 representing the upper portion of one side of the boiler section, the view being on a scale larger than Figure 1.

In the drawings, 2 designates generally a boiler section having an upper chamber 3. The plane of the normal water line of the boiler is indicated at 4. The portion of the chamber 3 above the water line constitutes a steam chamber, while the portion below the water line constitutes a water chamber. The section is shown as having a nipple port 5 in the side face thereof, the nipple port being centrally positioned with respect to the vertical axis of the section and being so disposed that a part of the nipple port is below the water line and a part of it above the water line. Formed in the top of the section at the center thereof, is a steam take-off connection 6. The boiler section below the chamber 3 is formed with flue passages therethrough, the particular section illustrated being shown as having a central flue 7 and a side flue 8. The presence of these flues forms on the interior of the section, water channels 9 between the flues 7 and 8, and water channels 10 between the flues 8 and the outside of the boiler. Below the flues 7 and 8 there is a water space 11 which communicates with water spaces 12 in the leg portions of the section. It will be understood that this section is merely typical of the general class of sections to which the present invention pertains and that the invention is not restricted to the particular arrangement of flues or other matters of design.

In the operation of the boiler sections steam is generated much more rapidly in the water channels 9 than in the water channels 10, so that there is an area at the water line over these channels 9 where steam leaves the water at a relatively higher rate than it does from other areas over the water line. Also there is greater turbulence at the water line by reason of the upward motion of the currents of water underlying the surface. In Figure 3 the arrows below the water line indicate generally the direction of flow of the water below the water line, while the arrows in the steam space indicate the direction of flow of the steam.

According to the present invention, I provide in the boiler over those areas where steam is generated at a higher rate, baffles 13. There are two baffles 13 shown, one being located at each side of the vertical center line of the section, one of them being located in the area of the boiler over one of the water circulating passages 9, and the other of them being similarly located in the area over the other passage 9. These baffles which are generally inclined and preferably curved, have the lower end thereof terminating below the plane of the normal water line. They are inclined or curved upwardly and outwardly from a point below the normal water line toward the outer walls of the section. They extend across the full depth of the section and, in the case of a cast iron section, are integrally cast. The steam which is generated at a high rate in the area beneath the baffles 13 rises from the surface of the water and is deflected by the baffles in a horizontal direction away from the steam outlet connection 6. When the steam clears the baffle, it rises upwardly and then turns horizontally back toward the center of the boiler so that in clearing the baffle it turns through an

arc of 180°. In leaving the take-off 6, it must again change its direction of flow 90° from a horizontal line. In so changing its direction of flow, entrained water particles, being of greater mass, change their direction less readily and are, therefore, thrown out of the steam.

By reason of the fact that the baffles have their inner lower ends terminating below the normal water line, it is impossible for any steam leaving the water surface in this particular area to by-pass the baffle and flow directly from the surface of the water to the outlet. Steam is generated at a relatively slower rate in that area of the boiler between the two baffles and this steam can flow without substantial deflection directly to the outlet. The turning of the steam through an angle of 180° as it clears the baffle results in a considerable amount of the moisture being thrown out, and the reverse flow through an arc of 90° in going from the steam chamber to the take-off further eliminates water. After the water has been thrown out of the steam which is carrying it, it is not again picked up to any considerable extent by the adjacent bodies or currents of steam.

The disposition of the baffles in the manner described permits of the same sections being used for hot water heating systems where the entire section is filled with water, as it does not restrict the circulation of the water in such case, and by reason of the inclination or curvature sediment would not accumulate on it to an undesirable extent. Thus the boiler sections are readily adapted for use in either type of heating plant, notwithstanding the presence of these baffles.

While I have shown and described a particular boiler section and a particular location of the baffles in regard to this specific section, it will be understood that the invention may be otherwise embodied and that various changes and modifications may be made within the contemplation of the appended claim.

I claim:

A boiler section having an upper portion forming a combined steam and water chamber, the water line of the boiler defining the separation of the steam and water chambers, a nipple port on a side face of the section opening into the chamber, the normal water line being above the bottom of the nipple port, a centrally located steam outlet connection in the section above the nipple port, the section having flue openings therethrough forming water circulating spaces below the water line of the section, and baffles in the section over certain of said water circulating spaces, said baffles being generally inclined upwardly and outwardly away from the center of the section, the lower ends of the baffles nearest the center of the section terminating below the water line of the boiler section, the upper outer ends of the baffles terminating in the steam space below the top of the section and inwardly from the side thereof, the arrangement being such that steam generated below the baffles is directed in a generally horizontal direction away from the center of the boiler and then turns at an angle of approximately 180° back toward the center of the boiler and is further deflected through a reverse angle of approximately 90° in passing to the offtake.

LOUIS N. HUNTER.
